UNITED STATES PATENT OFFICE.

RUDOLPH R. SIEBERT, OF ROCHESTER, NEW YORK, ASSIGNOR TO ART IN BUTTONS, INC.,
OF ROCHESTER, NEW YORK, A CORPORATION OF NEW YORK.

BUTTON.

1,318,235.

Specification of Letters Patent.

Patented Oct. 7, 1919.

Application filed December 6, 1918. Serial No. 265,624.

To all whom it may concern:

Be it known that I, RUDOLPH R. SIEBERT, a citizen of the United States, and resident of Rochester, in the county of Monroe and 5 State of New York, have invented certain new and useful Improvements in Buttons, of which the following is a specification.

The present invention relates to buttons, more particularly to the type in which the 10 button body has a shank embedded therein for the purpose of connecting such shank with the body. An object of this invention is to provide an improvement on the shank shown in the application of Lloyd A. Angle, 15 filed Aug. 22, 1918, Serial No. 251,035. A further object of this invention is to provide an improved shank which may be made from wire stock with an anchoring portion so formed as to permit the shank to be 20 driven into the button body to obtain a firm anchorage therein, while at the same time preventing the rotation of the shank in the body.

To these and other ends the invention 25 consists of certain parts and combinations of parts, all of which will be hereinafter described and more particularly pointed out in the appended claims.

In the drawing:

30 Fig. 1 is an edge view of the shank constructed in accordance with the present invention;

Fig. 2 is a side view of the same shank;

Fig. 3 is a section on the line 3—3 of

35 Fig. 2;

Fig. 4 is a section on the line 4—4, Fig. 2;

Fig. 5 is a section on the line 5—5, Fig. 2;

40 Fig. 6 is a detail view of the rear face of the button body showing the circular opening formed therein before the shank is driven into the body.

Fig. 7 is an enlarged sectional view of the button body showing a shank in position on the body; and

45 Figs. 8 and 9 are two views of the button complete.

In the before mentioned application of Lloyd A. Angle, filed August 22, 1918, Serial No. 251,035, a button is provided in which 50 the body consists of resilient material such as vulcanized fiber, or leather board, and into this body a shank is forced; the body in the first instance being provided with an opening in its rear face and the shank having an anchoring portion formed with an

enlargement of a greater cross-section than the opening of the body, the anchoring portion of the shank being forced into the opening while the button body is in a dry state and the material of the button body crowding behind the shoulder formed on the shank by the enlargement. In the before mentioned application the shank is illustrated as being formed from a solid piece of metal which must be cut or stamped to give it the 60 desired shape, whereas according to this invention, the shank is formed from wire stock and, in the illustrated construction, this stock is bent midway between its ends to provide an eye portion 1 at the bend, and 65 anchoring portion at the ends which are brought into abutment, the opposed abutting faces 2 of the anchoring portion, preferably being flattened as illustrated in Fig. 5 of the drawing. The outer faces of the anchoring 70 portion of the shank at the ends of the stock are provided with converging surfaces 3, and above these converging surfaces shoulders 4 are formed, these converging surfaces as well as the shoulders 4 defining the 75 enlargement at the end of the anchoring portion of the shank. Above the shoulder 4 the anchoring portion has two converging outer faces 5 which merge into the outer faces of the eye 1. Preferably these 80 converging faces and the shoulders 4 are formed by reducing the wire stock transversely by compression.

The button body 6, as in the Angle application No. 251,035 hereinbefore referred 85 to, is made of resilient material and is bored in its rear face to provide a pocket 7. Into this pocket, the anchoring portion of the shank is driven until the parts assume the positions indicated in Fig. 7. The diameter 90 of the opening 7 is less than the greatest diameter of the enlargement of the anchoring portion of the shank. When the enlargement is driven into the button body, the material expands above the shoulders 4 and 95 100 is again compressed by the converging faces 5 of the anchoring portion, the shank being driven into the button to those portions of the converging faces which are separated apart a distance at least as great as the 105 greatest diameter of the enlarged portion so that the opening in the rear face of the button body will be completely filled by the base of the anchoring portion, thus preventing any movement on the shank in the 110

button body. The cross-sectional form of the button shank is non-circular and this prevents any rotation of the shank in the button body.

5 From the foregoing it will be seen that there has been provided a shank which may be made from wire stock and driven into a button body made of resilient material to form a firm connection between the shank 10 and the button body, preventing any rotation of the shank in the button body, or in fact any movement whatsoever of the shank in the button body.

15 What I claim as my invention and desire to secure by Letters Patent is:—

1. A button comprising a button body and a button shank including an eye and an anchoring portion, both formed from a single piece of wire stock bent between its 20 ends, the eye being arranged at the bend, the anchoring portion being formed by portions near the ends, the opposed faces near the ends lying in abutment, and the anchoring portion having outer faces formed with converging portions which extend to the extreme 25 ends of the stock.

2. A button comprising a button body, and a button shank including an eye and an anchoring portion, both formed from a single piece of wire stock bent between its 30 ends, the eye being arranged at the bend, the anchoring portion being formed by portions near the ends, an anchoring portion having outer faces formed with converging portions

which extend to the extreme ends of the stock, and each outer face being provided with a shoulder above its converging portion.

3. A button comprising a button body, and a button shank including an eye and an anchoring portion, both formed from a single piece of wire stock bent between its 40 ends, the eye being arranged at the bend, the anchoring portion being formed by portions near the ends, the anchoring portion having outer faces formed with converging portions which extend to the extreme 45 ends of the stock and the outer faces being provided with shoulders above the converging portions and also with faces 50 above said shoulders converging with relation to each other.

4. A button comprising a button body and a button shank formed from wire stock bent upon itself to provide an eye, an anchoring portion, the eye being formed at the bend, the anchoring portion being formed by portions near the two ends of the stock beyond the eye, the opposed faces 55 of the stock in the anchoring portion being flattened and lying in abutment, and the outermost faces of said anchoring portion having converging portions extending to the extreme of the stock and being provided with shoulders above said converging portions. 60

RUDOLPH R. SIEBERT.
